(57) **CLAIM**

The ornamental design for a flexure element for load cell, as shown.

DESCRIPTION

FIG. 1 is a front elevational view of a flexure element for a load cell showing my new design;

FIG. 2 is a rear elevational view thereof;

FIG. 3 is a right side elevational view thereof with the left side view being a mirror image thereof;

FIG. 4 is a top plan view thereof;

FIG. 5 is a bottom plan view thereof; and,

FIG. 6 is a perspective view thereof.
